Primary Examiner — Paul D Bohannon

(74) Attorney, Agent, or Firm — Heslin Rothenberg Farley & Mesiti P.C.

(57) CLAIM

The ornamental design for a seat, as shown and described.

DESCRIPTION

This application is related to commonly assigned, co-filed U.S. design patent application Ser. No. 29/792,478, filed on Mar. 31, 2022, by Matthew Plumstead entitled "Stool"; commonly assigned, co-filed U.S. design patent application Ser. No. 29/792,479, filed on Mar. 31, 2022, by Matthew Plumstead, entitled "Bench"; commonly assigned, co-filed U.S. design patent application Ser. No. 29/792,480, filed on Mar. 31, 2022 by Matthew Plumstead, entitled "Table"; commonly assigned, co-filed U.S. design patent application Ser. No. 29/792,481, filed on Mar. 31, 2022, by Matthew Plumstead, entitled "Table"; commonly assigned, co-filed U.S. design patent application Ser. No. 29/792,482, filed on Mar. 31, 2022, by Matthew Plumstead, entitled "Seat"; and commonly assigned, co-filed U.S. design patent application Ser. No. 29/792,483, filed on Mar. 31, 2022, by Matthew Plumstead, entitled "Table", which applications are incorporated herein by reference in their entireties.

FIG. 1 is a front right perspective view of a seat according to the new design;

FIG. 2 is a rear left perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof;

FIG. 8 is a bottom view thereof;

FIG. 9 is a front right perspective view thereof, shown with a symbolic break in length, which is the sole difference between it and FIGS. 1-8; and,

FIG. 10 is a front right perspective view thereof, shown with a symbolic break in length, which is the sole difference between it and FIGS. 1-8.

The broken lines shown in FIGS. 1-10 illustrate portions of the environment and the seat and form no part of the claimed design.

The wave shaped dash-dash broken lines in FIGS. 9 and 10 indicate a symbolic break in the length of the design. Any portion of the article between the breakaway lines forms no part of the claimed design.

1 Claim, 10 Drawing Sheets
